UNITED STATES PATENT OFFICE.

CHARLES T. WESTLAKE, OF ST. LOUIS, MISSOURI, ASSIGNOR TO COMMONWEALTH STEEL COMPANY, OF ST. LOUIS, MISSOURI, A CORPORATION OF NEW JERSEY.

SEPARABLE BODY-BOLSTER.

1,114,209.

Specification of Letters Patent.

Patented Oct. 20, 1914.

Application filed May 16, 1913. Serial No. 768,051.

To all whom it may concern:

Be it known that I, CHARLES T. WESTLAKE, a citizen of the United States, residing at the city of St. Louis, State of Missouri, have invented a certain new and useful Improvement in Separable Body-Bolsters, of which the following is a full, clear, and exact description, such as will enable others skilled in the art to which it appertains to make and 10 use the same, reference being had to the accompanying drawings, forming part of this specification, in which—

Figure 1 is a top plan view of a separable body bolster of my improved construction. 15 Fig. 2 is a side elevational view of my improved bolster and showing the center sill with which said bolster is combined, in section. Fig. 3 is a vertical sectional view taken approximately on the line 3—3 of Fig. 2 and 20 showing the end sill of a car underframe and the draft sills, which are positioned between the ends of the center sills and said end sill. Fig. 4 is a vertical section taken approximately on the line 4—4 of Fig. 3. Fig. 5 is 25 an enlarged cross sectional view taken approximately on the line 5—5 of Fig. 1. Fig. 6 is a view of the underside of the separable center bearing plate forming a part of my improved bolster.

This invention relates to new and useful 30 improvements in separable body bolsters, that is, a body bolster having a portion which can be easily and quickly applied or detached so as to permit the bolster to be 35 readily combined with the center sills and draft sills of a car underframe.

The principal objects of my invention are 40 to construct a simple inexpensive body bolster of cast metal and to form an opening or openings through the central portion of said bolster for the accommodation of the center sills of the underframe; to provide a readily detachable center plate which spans the 45 openings or openings in the bolster, which plate is provided with a center bearing, and further, to provide a simple, strong and rigid car underframe construction including my improved separable body bolster, center sills, and draft sills, which construction can 50 be easily assembled, or in the case of repairs can be easily taken apart.

To the above purposes, my invention consists in certain novel features of construction

and arrangement of parts hereinafter more fully described and claimed.

As shown in the drawings, my improved separable body bolster is combined with a pair of center sills, each comprising a vertically disposed web plate 10, to the upper and lower edges of which are fixed angles 11, the same being arranged so that their horizontal flanges are outwardly presented. Positioned on top of the center sills thus formed and attached to the horizontal flanges of the upper pair of angles 11 is a 65 cover plate 12. The web plates 10 of the center sills are provided in their ends with longitudinally disposed slots 13 for the accommodation of the top flange of the body bolster. This body bolster is preferably 70 cast in a single piece and comprises a vertically disposed web 14, a top flange 15, and a bottom flange 16. Thus said bolster is substantially of I-beam shape in cross section.

The central portion of the body bolster is preferably depressed with respect to its ends so that the tops of the side sills 17 of the underframe to which the ends of the bolster are attached occupy substantially the same 80 horizontal plane with the top plate 12.

Formed integral with the web 14 at the center of the bolster is a vertically disposed hollow cylindrical housing 18 with the bottom of which is formed integral a depending 85 lug 19. The top flange 15 above this housing 18 and the lug 19 are perforated to receive a king bolt. Formed through the web 14 of the bolster near the center thereof an equal distance from the housing 18 are openings 20 which accommodate the lower portions of the center sills when the bolster is 90 properly positioned on said center sills.

The slots 13 in the web plate 10 of the center sills are, in length, approximately twice 95 the width of the top flange of the body bolster, and thus when said body bolster is properly positioned on the center sills the ends thereof project a short distance beyond the body bolster.

Formed integral with the web 14 adjacent to the inner edges of the openings 20 are web plates 21 which are arranged at right angles to the web 14 and these web plates bear directly against and are fixed to the web plates 105 10 of the center sills.

Formed in the underside of the bottom flange 16 adjacent to the openings 20 are recesses 22 which receive the ends of the separable member forming a part of my improved bolster. This member comprises a plate 23 which is adapted to be applied to the underside of the bolster beneath the center sills, and formed integral with the underside of this plate is a center bearing 24 which is perforated to accommodate the king pin. The upper portion of this plate is provided with an annular recess 25 which accommodates the lug 19 that is formed on the underside of the housing 18.

Formed integral with the ends of the plate 23 and on top thereof are transverse ribs or lugs 26 which, when the plate is properly applied to the bolster, bear directly against the shoulders at the inner ends of the recesses 22, thereby providing effective ties beneath the openings 20 and forming an interlocking connection between the ends of the plate 23 and the lower portion of the bolster outside said openings, and which construction resists any tendency of the bolster to break or fracture above the openings 20 when the ends of said bolster are jacked up to permit repair or removal of a truck. The ends of the plate 23 bear directly against the shoulders at the outer ends of the recesses 22 and by such construction the plate 23 performs the functions of a compression member to resist abnormal load strains imposed on the outer portions of the bolster.

The ends of this separable plate are detachably connected to the bottom flange 16 of the bolster by means of fastening devices 27, such as bolts or rivets. The end portions of this plate spans the spaces beneath the openings 20 and when the parts are properly assembled said plate is attached to the horizontal flanges of the lower pair of angles 11 by means of rivets or like fastening devices.

When the bolster is properly combined with the center sills a pair of draft sills 28 which are preferably channel-shaped in cross section are attached directly to the projecting portions of the web plates 10 and the angles 11 by means of rivets or like fastening devices, the rear ends of which draft sills bear directly against the front edge of the top flange 15 of the bolster. The outer ends of these draft sills are attached in any suitable manner to the end sill 29 of the car underframe.

The body bolster is preferably formed with integral side bearing members 30 and with projecting plates 31 which receive nail-
60 ing strips.

When my improved body bolster is combined with the center sills and before the draft sills are attached to said center sills it is preferable, although not necessary, that rectangular filler plates 32 are located against

the outer walls of the web plates 10 between the projecting portions of the angles 11, and the rivets utilized in attaching the draft sills to the center sills pass directly through these filler plates.

By slotting the center sills to accommodate a part of the body bolster and making a part of said body bolster separable, said bolster can be very easily and quickly applied to the center sills when the car underframe is assembled or in the case of repairs or renewal of parts it will be a comparatively easy matter to remove the body bolster from the center sills.

The separable plate 23 is in effect a tension member for the central portion of the bolster and by providing the transverse lugs or ribs 26 which bear against the shoulders at the inner ends of the recesses 22 the stresses and strains produced by the weight on the center of the bolster are resisted and such construction also relieves the fastening devices 26 of shearing strains.

That portion of the web 14 of the body bolster between the openings 20 and which portion includes the cylindrical member 18 constitutes a strut between the central portion of the top chord of the bolster comprising the flange 15 and the bottom chord or tension member comprising the plate 23.

My improved construction is comparatively simple, is strong and rigid, can be easily assembled, and in the case of repairs can be easily taken apart.

I claim:

1. In car construction, the combination with center sills provided in their ends with slots, of a body bolster connected to said center sills, a portion of which body bolster occupies said slots, and a plate detachably applied to said body bolster beneath the center sills.

2. In car construction, the combination with center sills provided in their ends with slots, of a body bolster connected to said center sills, a portion of which body bolster occupies said slots, a plate detachably applied to said body bolster beneath the center sills, and a center bearing on said plate.

3. In car construction, the combination with center sills provided in their ends with slots, of a body bolster connected to said center sills, said body bolster having a top flange which occupies said slots, and a detachable center bearing plate applied to the bolster beneath the center sills.

4. In car construction, the combination with center sills provided in their ends with slots, of a body bolster having openings, a portion of which body bolster occupies the slots in the center sills, parts of which center sills project through the openings in the body bolster, and a plate detachably applied to the bolster beneath the center sills, and the openings in said body bolster.

5. In car construction, the combination with center sills provided in their ends with slots, of a body bolster having openings to accommodate parts of the center sills below the slots therein, and a separable center bearing plate attached to the body bolster below the openings therein. 5
6. In car construction, the combination with center sills provided in their ends with slots, of a body bolster having openings to accommodate parts of the center sills below the slots therein, a separable center bearing plate attached to the body bolster below the openings therein, and draft sills fixed to the projecting portions of the center sills. 10
7. A railway car body bolster provided near its center with openings, center sills projecting entirely through the openings in the bolster, which sills are provided with slots which receive a part of said bolster, and a plate detachably applied to the underside of said bolster below the openings therein. 20
8. A railway car body bolster provided near its center with openings, center sills projecting entirely through the openings in the bolster, which sills are provided with slots which receive a part of said bolster, and a center bearing plate applied to the underside of said bolster below the openings therein which plate is fixed to the center sills and to the bolster. 25
9. A car body bolster provided near its center with openings, center sills projecting entirely through the openings in the bolster, which sills are provided with slots which receive a part of said bolster, a plate detachably applied to the underside of the bolster below the openings therein which plate is fixed to the center sills and to the bolster, and lugs on said plate, which lugs engage against shoulders formed on the underside of the bolster. 35
10. In car construction, the combination with center sills, of a body bolster, parts of which bolster pass through openings formed in the center sills, parts of which center sills project through openings in the body bolster, and a separable center bearing plate applied to the bolster beneath the openings therein and beneath the center sills. 45
11. In car construction, the combination with center sills, of a body bolster, parts of which bolster pass through openings formed in the center sills, parts of which center sills project through openings in the body bolster, a separable center bearing plate applied to the bolster beneath the openings therein and beneath the center sills, and draft sills attached to the projecting portions of the center sills. 55
12. In car construction, the combination with center sills, of a body bolster, parts of which bolster pass through openings formed in the center sills, parts of which center sills project through openings in the body bolster, said bolster being provided in its underside with recesses adjacent to the openings therein, and a separable center bearing plate applied to the underside of the body bolster with the ends of said plate seated in said recesses. 60
13. In car construction, the combination with center sills provided in their ends with slots, of a body bolster combined with said center sills, a portion of which body bolster occupies said slots, a center bearing plate detachably applied to the bolster beneath the center sills, and a strut between the center bearing plate and the top flange of the bolster. 70
14. In car construction, the combination with center sills provided in their ends with slots, of a body bolster combined with said center sills, a portion of which body bolster occupies said slots, a center bearing plate detachably applied to the bolster beneath the center sills, and a strut integral with the body bolster, which strut is engaged by the center bearing plate. 80
15. In car construction, the combination with center sills provided in their ends with slots, of a body bolster combined with said center sills, a portion of which body bolster occupies said slots, a center bearing plate detachably applied to the bolster beneath the center sills, and a strut between the separable center bearing plate and the top flange of the bolster, which strut is positioned beneath the center sills. 90
16. A car body bolster provided near its center with openings adapted to receive parts of slotted sills, a separable center bearing plate applied to the bolster beneath the openings therein, and a strut formed by that portion of the bolster between said openings, which strut is engaged by the center bearing plate. 105
17. In car construction, a slotted center sill, a body bolster provided near its center with an opening adapted to receive the slotted center sill so that a portion of the latter extends through said bolster, a plate detachably applied to the underside of the bolster below the opening therein, which plate is provided with shoulders which cooperate with shoulders on the bolster to resist tension which may be imparted to said plate. 110
18. In a car underframe, a center sill, the end portion of which is slotted, a body bolster provided near its center with an opening adapted to receive the slotted end of the center sill, a plate applied to the bolster beneath the opening therein, the ends of which plate are connected to said bolster so that said plate performs the functions of a tension member or a compression member, corresponding to the strains imparted to the bolster. 120
19. In a car underframe, a center sill, the end portion of which is slotted, a body bolster provided near its center with an opening adapted to receive the slotted end of the center sill, a plate applied to the bolster beneath the opening therein, the ends of which plate are connected to said bolster so that said plate performs the functions of a tension member or a compression member, corresponding to the strains imparted to the bolster. 130

19. In a car underframe, a center sill, the end of which is slotted, a body bolster having an opening adapted to receive the slotted end of the center sill; there being recesses in the underside of the bolster to the sides of the opening therein, a plate applied to the bolster beneath the opening therein, and co-operating shoulders on the bolster and plate whereby the latter performs the functions of a tension member, a compression member, corresponding to the strains imparted to the bolster.

20. In car construction, an underframe having a center sill, the end of which is slotted, a body bolster provided with an opening adapted to receive the slotted end of the center sill, which bolster is provided

with recesses adjacent to the sides of the opening, and there being shoulders at the ends of said recesses, of a plate applied to said bolster beneath the opening therein, shoulders on the plate which coöperate with the shoulders at the inner ends of the recesses, and the ends of which plate engage the shoulders at the outer ends of the recesses.

In testimony whereof I hereunto affix my signature in the presence of two witnesses, this 6th day of May, 1913.

CHARLES T. WESTLAKE.
